US00D822849S

(12) **United States Design Patent** (10) **Patent No.:** **US D822,849 S**
(45) **Date of Patent:** **** Jul. 10, 2018**

(54) **OFFICE BOOTH**

(71) Applicant: **CLESTRA HAUSERMAN**, Illkirch
Graffenstaden (FR)

(72) Inventor: **Paul Levy**, Illkirch (FR)

(**) Term: **15 Years**

(21) Appl. No.: **35/503,262**

(22) Filed: **Mar. 20, 2017**

(80) **Hague Agreement Data**

Int. Filing Date: **Mar. 20, 2017**

Int. Reg. No.: **DM/096488**

Int. Reg. Date: **Mar. 20, 2017**

Int. Reg. Pub. Date: **Jun. 30, 2017**

(51) **LOC (11) Cl.** **25-02**

(52) **U.S. Cl.**

USPC **D25/35; D25/33**

(58) **Field of Classification Search**

USPC D25/1, 16, 32, 33, 35; D6/640, 641

CPC E04H 1/1205

See application file for complete search history.
